(57) CLAIM

The ornamental design for a shoe, as shown and described.

DESCRIPTION

FIG. 1 is a front left perspective view of a shoe showing our new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The elongated dashed lines in FIGS. 1-7 represent a stitched pattern and form part of the claimed design. Moreover, FIGS. 1-7 include short broken lines for the purpose of illustrating portions of the shoe that form no part of the claimed design, as well as stitching along the collar and the outsole that also forms no part of the claimed design. The material shading shown in FIGS. 1-7 represents a knitted textile and forms part of the claimed design.
